T. E. WALKER

TENSION DEVICE FOR CASEMENT WINDOWS

Filed Dec. 1, 1921

Patented Aug. 7, 1923.

1,464,229

UNITED STATES PATENT OFFICE.

THOMAS E. WALKER, OF DETROIT, MICHIGAN, ASSIGNOR TO CRITTALL CASEMENT WINDOW CO., OF DETROIT, MICHIGAN, A CORPORATION OF MICHIGAN.

TENSION DEVICE FOR CASEMENT WINDOWS.

Application filed December 1, 1921. Serial No. 519,051.

To all whom it may concern:

Be it known that I, THOMAS E. WALKER, a citizen of the United States of America, residing at Detroit, in the county of Wayne 5 and State of Michigan, have invented certain new and useful Improvements in Tension Devices for Casement Windows, of which the following is a specification, reference being had therein to the accompanying 10 drawings.

In my Patent No. 1,382,578, granted June 21, 1921, there is disclosed a window or frame and sash construction which includes a metallic channel frame, a transverse hinge member having angular ends slidable in said frame, a sash hinged to said transverse hinge member, and springs interposed between the side rails of the sash and the side rails of the frame. The springs engage wear plates 15 within the channel rails of the frame and the tension of the springs may be increased or decreased, by tightening or loosening screws, so that there is a proper and uniform sliding contact between the sash and the frame for holding the sash in any position to which it may be raised. The compression springs are comparatively flat and the manner of mounting the springs necessitated considerable labor and some skill in 20 order to equally regulate the tension of the springs at both sides of the sash, so as to prevent one side from binding more than the other. Then again, constant use necessitated regulating the tension of the springs 25 from time to time and at each side of the frame there is only one surface engaged by the spring, consequently it was necessary to use a comparatively stiff spring in order that the sash might be held in an adjusted position.

This invention relates to tension or take-up devices that are easier to install and more positive in their operation than the springs disclosed in my prior patent. Instead of 30 using flat springs in connection with single contact surfaces, I now use coiled compression springs in connection with opposed compression members and the compression members are arranged to engage two contact surfaces and provide a more binding and more positive device for holding a sash to a shifted position. It is unnecessary to 35 regulate the tension of the device which I now employ and when once installed the devices will automatically compensate for wear

and at all times insure a positive frictional contact between the sash supporting means and the frame of a window.

Other advantages are gained which will appear as the invention is hereinafter described, and reference will now be had to the drawing, wherein—

Figure 1 is a vertical fragmentary transverse sectional view of a window frame and sash showing the hinge member of the 45 sash provided with a tension device in accordance with this invention;

Fig. 2 is a vertical cross sectional view of the same taken on the line II—II of Fig. 1;

Fig. 3 is a horizontal sectional view taken 50 on the line III—III of Fig. 1;

Fig. 4 shows views of modified forms of compression members;

Fig. 5 is a front elevation of a transverse hinge member relative to a portion of the 55 frame which is shown in section, and

Fig. 6 shows detail views of modified forms of compression members.

In the drawing the reference numerals 1 denote the channel side rails of a frame and 60 suitably mounted in the channels of said rails are channel wear members 2.

Slidable in the channel wear members 2 are angular ends or heads 3 of a transverse hinge member 4 and hingedly connected to 65 this member is the upper rail 5 of a sash 6, said sash having side rails 7 adapted to engage the side rails 1 of the frame.

The upper ends of the heads 3 have cam members 8 which insure proper closing of an 90 upper sash (not shown). The lower ends of the heads 3 are identical in construction, so I deem it only necessary to describe the lower end of one head with special reference to Figs. 1 and 2.

The lower end of the head 3 has its outer face provided with a seat 9 for the upper end of a retaining member 10, said retaining member having its upper end secured on the seat by screws 11 or other fastening means 100 and the lower end of the retaining member is inturned into the wear member 2 to provide a support 12 for opposed compression members 13 and 14. These members have the upper ends thereof loose on seats 15 provided therefor in the side walls of the head 3 and the lower ends of the members are inturned, as at 16, so as to provide a substantial footing or base for said members on the support 12. The compression members 13 110

normally contact with the side walls 17 of the wear member 2 and to maintain this frictional contact coiled expansion springs 18 are interposed between the members 13 and 14.

Separating the coiled expansion springs 18 are overlapping inbent portions 19 and spaced inbent portions 20 of the compression members 13 and 14, said inbent portions providing compartments for the compression springs 18. The inbent portions 19 and 20 of the members 13 and 14 are located so that some of the inbent portions will simply provide partitions between the springs 18 and other inbent portions of the member 13 engage inbent portions of the member 14, these overlapping or contacting inbent portions serving as guides during any shifting of the compression members. With the compression members placed in a channel or wear member 2 the retaining member 10 will cooperate with the channel wear member in providing an enclosure for said compression members and the expansion springs therebetween, so that there is a complete housing at the lower end of the head which prevents accidental displacement of any part of the tension device while being shifted in the channel wear member. With the compression members engaging opposite walls of the channel wear member there is a double frictional contact at each side of the sash compared to the single frictional contact in my prior patent, and since the compression members are long with wide contact faces it is obvious that there will be a substantial bearing for said compression members against the channel wear member, with equal pressure throughout the length of each compression member.

As shown in Fig. 4 the inbent portions 21 of one compression member may overlap the inbent portions of the opposed compression member, also that each compression member may have inbent portions 22 which simply serve as spacers, without overlapping. Furthermore, instead of each compression member having an inturned lower end just one of the compression members may have such an end extending to the other compression members. As a matter of fact the compression members may have various configurations by which said members may guide each other when shifted or provide separate compartments for the expansion springs.

As a further instance of spacing the springs, I show in Fig. 6 opposed members 25 having inturned ends 26 and pressed out teets or bosses 27 for the end convolutions of springs 28. The bosses 27 will maintain the springs in spaced relation, against accidental displacement, and with this form of compression members it is unnecessary to provide the seats 15 in the heads 3. The inbent ends 26 will readily ride against the ends of

said heads and the support 12 when said members are shifted.

When the transverse hinge member 4 is shifted in the rails 1 of the window frame, the tension devices at the ends of the member 4 will hold said member against accidental displacement, yet permit of the hinged member being manually shifted when occasion requires.

While in the drawings there are illustrated the preferred embodiments of my invention, it is to be understood that the structural elements are susceptible to such variations and modifications as fall within the scope of the appended claims.

What I claim is:—

1. In a window frame, a sash supporting member that may be adjusted, said member having ends slidable in said frame, means on the ends of said member engaging walls of the frame for holding the sash supporting member in an adjusted position, said means comprising opposed compression members at each end of the sash supporting member, and springs between said compression members.

2. A window construction as in claim 1, wherein said compression members have a configuration providing separate compartments for the springs.

3. In a window, the combination of a frame, a hinge member having ends slidable in said frame, a sash hinged to said hinge member, means adapted to frictionally hold the ends of said hinge member against accidental movement in said frame, said means comprising opposed compression members at each end of said hinge member constantly producing pressure against front and rear portions of said frame.

4. The combination called for in claim 3, and retaining members carried by the ends of said hinge member and supporting said compression members relative thereto.

5. The combination called for in claim 3, wherein said compression members have a configuration affording compartments, and springs are placed in said compartments to hold said compression members normally distended.

6. In a window, the combination of a frame, a hinge member having ends slidable in said frame, a sash connected to said hinge member, tension devices at the ends of said hinge member, each device comprising a retaining member depending from the end of said hinge member, a compression member supported by said retaining member and frictionally holding the end of said hinge member relative to said frame, and an expansion spring bearing against said compression member.

7. In a window, the combination of a frame, a hinge member having ends slidable in said frame, a sash connected to said

- hinge member,—tension devices at the ends of said hinge member, each device comprising a retaining member depending from the end of said hinge member, compression members supported by said retaining member, and springs between said compression members, said retaining members and compression members providing a housing for said springs.
8. The combination called for in claim 7, wherein the compression members engage

opposed walls at each side of said sash and said compression members have configurations affording compartments for said springs. 15

In testimony whereof I affix my signature in presence of two witnesses.

THOMAS E. WALKER.
